UNITED STATES PATENT OFFICE.

SAMUEL ROWAN, OF NEW YORK, N. Y.

DESIGN FOR A CALENDAR.

SPECIFICATION forming part of Design No. 20,856, dated June 23, 1891.

Application filed May 6, 1891. Serial No. 391,820. Term of patent 3½ years.

To all whom it may concern:

Be it known that I, SAMUEL ROWAN, a citizen of the United States, residing at New York city, State of New York, have invented and 5 produced a new and original Design for Perpetual Calendars, of which the following is a specification, reference being had to the accompanying drawings, forming part thereof.

The figure is a front or vertical view of a 10 calendar, showing my design.

The leading feature of my design consists in the ornamentation of the frame with a

scroll, shell, and flower designs in the manner shown in the drawing. I do not claim either of these alone, but as grouped in the manner 15 shown.

What I claim is—

The design for a calendar, substantially as shown.

SAMUEL ROWAN.
